230,324

RADIOISOTOPE GENERATOR

John D. Wark, Freeport, and Henry A. Holzwarth, Bay-side, N.Y., assignors to Mallinckrodt Chemical Works, St. Louis, Mo.

Filed Aug. 26, 1971, Ser. No. 175,416

Term of patent 14 years

Int. Cl. D24—02

U.S. Cl. D83—1 H

FIG.1

FIG.2

FIG.3

FIG.4

FIG.5

FIG.6

FIG.7

FIG. 1 is a perspective of a radioisotope generator embodying our new design;

FIG. 2 is a top plan view of FIG. 1;

FIG. 3 is a front elevation of FIG. 1;

FIG. 4 is a left side elevation of FIG. 1;

FIG. 5 is a right side elevation of FIG. 1;

FIG. 6 is a rear elevation of FIG. 1; and

FIG. 7 is a bottom plan of FIG. 1.

We claim:

The ornamental design for a radioisotope generator, substantially as shown.
